(57) **CLAIM**

We claim the ornamental design for an infant's stuffed dog with thumb pacifiers, as shown and described.

DESCRIPTION

FIG. 1 is a perspective view of an infant's stuffed dog with thumb pacifiers, showing our new design, the right arm being shown in a downward position;

FIG. 2 is a front elevational view thereof;

FIG. 3 is a rear elevational view thereof;

FIG. 4 is a left side elevational view thereof, the right side elevational view being a mirror image thereof;

FIG. 5 is a top plan view thereof; and,

FIG. 6 is a bottom plan view thereof.
